CLAIM

The ornamental design for a combined otoscope speculum and cleaning loop, as shown and described.

DESCRIPTION

FIG. 1 is a perspective view of a combined otoscope speculum and cleaning loop showing my new design; FIG. 2 is a top plan view thereof, the bottom plan view being a mirror image thereto;

FIG. 3 is a side elevational view thereof, the opposite side elevational view being a mirror image thereto;

FIG. 4 is a front end elevational view thereof;

FIG. 5 is a rear end elevational view thereof;

FIG. 6 is a perspective view of a second embodiment of the combined otoscope speculum and cleaning loop;

FIG. 7 is a top plan view thereof, the bottom plan view being a mirror image thereto;

FIG. 8 is a side elevational view thereof, the opposite side elevational view being a mirror image;

FIG. 9 is a front end elevational view thereof; and,

FIG. 10 is a rear end elevational view thereof.

FIG 5FIG 2FIG 3FIG 4

FIG. 10FIG. 11FIG. 12FIG. 13
